UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

ADDRESSING MACHINE.

Application filed March 10, 1919, Serial No. 281,609. Renewed April 6, 1920. Serial No. 371,722.

To all whom it may concern:

Be it known that I, CLIFTON CHISHOLM, a citizen of the United States, residing at

5 Cleveland, in the county of Cuyahoga and State of Ohio, have invented a certain new and useful Improvement in Addressing Machines, of which the following is a full, clear, and exact description.

In a certain type of addressing machine, 10 such for example, as that shown and described in my prior Patent No. 1,285,622, there is a rotating cylindrical platen, and mechanism, associated therewith, by which envelopes are withdrawn one by one from a 15 hopper and carried around in surface contact with said platen to printing mechanism; and there is also mechanism by which address plates are withdrawn one by one from a hopper and carried to said printing 20 point at such a rate that each envelope will be met by an address plate and the two will pass together through the printing mechanism, with the result that the address on each plate will be printed on an envelope. In 25 some of such machines, however, such as shown in my said prior patent, the envelope feeding mechanism may operate to feed only one envelope for each revolution of the platen and its shaft; or it may operate to 30 feed more than one envelope for each revolution of the platen; that is to say, there may be a fast or a slow feeding of the envelopes to the printing mechanism without any 35 change in the rate of revolution of the envelope feeding mechanism. Obviously, it is necessary that the address plates shall be carried to the printing point as fast as the envelopes are carried to it, whether the envelopes are being fed at the fast or slow rate.

40 The present invention consists of simple, durable, and inexpensive means by which the address plates will be carried to the printing mechanism in synchronism with the envelopes whether the rate of envelope feed be fast or slow,—all as shown in the accompanying drawings and hereinafter described and pointed out definitely in the appended claims.

45 In the drawing, Fig. 1 is a side elevation, from the left side of Fig. 2, of the present invention and so much of the machine of said prior patent as is necessary to disclose the manner of applying the present invention thereto. Fig. 2 is a sectional end view 50 of said mechanism in the plane of line 2—2

on Fig. 1; Fig. 3 is a longitudinal sectional view of the clutch mechanism to be presently described.

Referring to the parts by reference characters, 51 represents the main driving shaft 60 of an addressing machine, and 50 represents a cylindrical platen which is mounted upon and fixed thereto. This shaft carries envelope feeding mechanism such as is disclosed in said prior platen, including arms 65 55, pivoted to said shaft, and having fingers 58 for engaging the envelopes in a hopper (not shown). This envelope feeding mechanism, as described in said prior patent, will withdraw the envelopes one by one from the 70 hopper and carry them around in surface contact with the platen to the printing mechanism.

20 represents the address plate hopper which is organized to contain a stack of address plates. The upper stretches of two plate feeding endless chains 60 run through the bottom of this hopper beneath the lowest plate therein; and these chains carry upwardly projecting lugs 61 which engage the 80 lowest plate in the stack and withdraw it and carry it along resting on said chains until it passes between the platen 50 and a printing roller 64. Each chain runs over a sprocket wheel 63 mounted on a shaft 65, 85 and over other sprocket 75 which are fixed to a shaft 70.

In the present invention the printing roller 64 is loosely mounted on shaft 70 in such position that when a plate carried along by 90 said chains, and an envelope carried along with the platen pass between the platen and the printing roller, the plate and envelope will be pressed together and thereby the address on the plate is printed on the envelope. 95

The shaft 70 receives its motion from the main driving shaft 51 through either of two trains of gears, and means are provided by which either train may be rendered operative. In the particular construction shown 100 two intermeshing gears 71 and 72, are respectively mounted on the shafts 51 and 70,—the latter gear being twice the diameter of the other. Two other intermeshing gears 73 and 78 of the same diameter are respectively mounted on the shafts 51 and 70. The gears 72 and 78 are, however, fixed to shaft 70, while the gears 71, 73, are loosely mounted on the shaft 51. A simple clutch contrivance is provided by which either of these 110

last mentioned gears may be operatively connected with the shaft. To effect this result the gears carry on the proximate ends of their hubs lugs 77 which may be engaged by 5 a T-shaped finger 80 which is fixed to the outer end of an arm 81. This arm is fixed to an endwise movable rod which is mounted coaxially within the shaft 51, and projects out of a slot 51^a therein. By taking hold of 10 its projecting end this rod may be pushed inward to connect the larger gear 73 with shaft 51 or outward to connect the smaller gear 71 with shaft 51, and it may also occupy an intermediate position which connects neither gear to said shaft.

Having described my invention, I claim:—

1. In an addressing machine, the combination of printing mechanism, envelope feeding mechanism including a driving shaft therefor and mechanism operated by said shaft for carrying one or more envelopes to the printing mechanism during each revolution of said shaft, with address plate feeding mechanism for carrying address plates linearly to and through the printing mechanism,—which address plate feeding mechanism includes a driving shaft therefor, two trains of gearing for transmitting motion 20 from one of said shafts to the other, and means to render either train of gearing operative and the other inoperative.
2. In an addressing machine, the combination of envelope feeding mechanism including a driving shaft therefor, a cylindrical platen fixed to said shaft, and mechanism operated by said shaft whereby one or more envelopes are carried to the printing mechanism in surface contact with said cylindrical platen during each revolution of said shaft, with address plate feeding mechanism for carrying address plates to and through the printing mechanism including a driving shaft for said plate feeding mechanism, a 30 printing roller loosely mounted on the last mentioned shaft in printing relation to said platen, two trains of gearing for transmitting motion from one of said shafts to the other, and means to render either train of gearing operative and the other inoperative.

3. In an addressing machine, the combination of envelope feeding mechanism including a driving shaft therefor a cylindrical platen fixed to said shaft and means operated by said shaft for carrying one or two envelopes to and through the printing mechanism in surface contact with said platen during each revolution of said shaft, with address plate feeding mechanism including 40 a driving shaft therefor, two sprocket wheels fixed to said shaft, another shaft, two sprocket wheels fixed thereto, two endless sprocket chains which embrace said sprockets and have outwardly projecting plate-engaging lugs, a plate hopper through the

lower end of which the upper stretches of said chains pass, a printing roller loosely mounted on one of said shafts between the sprocket wheels thereon and in printing relation to said platen, two trains of gearing 70 for transmitting motion from one of said shafts to the other, and means to render either train of gearing operative and the other inoperative.

4. In an addressing machine, the combination of envelope feeding mechanism including a driving shaft therefor a cylindrical platen fixed to said shaft and means operated by said shaft for carrying one or two envelopes to the printing mechanism during 80 each revolution of said shaft, two gears of unequal diameter loosely mounted on said driving shaft, clutch mechanism by which to clutch either gear to said shaft, plate feeding mechanism for carrying address plates to and through the printing mechanism including a driving shaft therefor, two gears of unequal size fixed to the last mentioned shaft and in mesh with the two first gears mentioned, and a printing roller 90 loosely mounted on said shaft in printing relation with said platen.

5. In an addressing machine, the combination of printing mechanism, feeding mechanism for conveying impression receiving articles to the printing mechanism, mechanism for conveying address plates to said printing mechanism, means for synchronizing the movements of said two feeding mechanisms, and means to change the 100 relative rate of movement of said two feeding mechanisms.

6. The combination of means for feeding an article, separate means for feeding at a different speed an address plate into coacting position to act upon the article, and a member having the same angular speed as the article feeding means for feeding both the article and address plate after their coaction.

7. The combination of a platen, means for feeding an article to be printed, means for feeding at a different speed an address plate to act upon the article against the platen, and means whereby, after such action the article and the address plate are fed at the same angular speed as the article feeding means.

8. The combination of means for feeding an article, additional means for feeding a 120 printing member into position to impress the article, a rotary platen movable independently of the means for feeding the printing member and adapted to coact with the article feeding means, whereby the article and the printing member may be fed at the same angular speed.

9. In an addressing machine, the combination of mechanism for feeding address plates in a straight line to printing position,

and means for feeding impression receiving articles into cooperation with said address plates, and mechanism adapted to make the movement of the article feeding mechanism different multiples of that of the address plate feeding mechanism.

10. In an addressing machine, the combination of mechanism for conveying address plates successively, rotary mechanism for conveying impression-receiving articles successively into co-operation with the address plates, a loose platen, cooperating with said rotary mechanism to press between them the plate and impression receiving article the plate and the article then moving at the same contacting speed, and mechanism adapted to vary the movement of the article conveying mechanism with reference to that of the address plate conveying mechanism.

11. In an addressing machine, the combination of mechanism for feeding address plates and impression-receiving articles into cooperation, and mechanism adapted to make the movement of the article feeding mechanism different multiples of that of the address plate feeding mechanism, and a platen adapted to coact with the article feeding mechanism to receive a plate therebetween, said platen being movable independently of the plate feeding mechanism.

12. In an addressing machine, the combination of printing mechanism, movable mechanism for conveying impression receiving articles to the printing mechanism, movable mechanism for conveying address plates to said printing mechanism, means to change the relative rate of movement of said two conveying mechanisms, and an independently movable platen adapted to press the plate and impression receiving article into printing contact.

13. The combination with a pair of rollers, of independent means for feeding address plates between them, means for feeding impression receiving articles between them, and means for varying the feed to provide for a different number of articles for each rotation of the article feeding roller.

14. The combination with a pair of rollers, of means for feeding address plates between them, means for feeding impression receiving articles between them, the articles being fed at the same peripheral speed as the roller adjacent thereto while the plate may have a different speed from that of the roller adjacent to it.

15. The combination of a pair of coacting rollers, an envelope feed associated with one roller, a plate feed associated with the other roller, said other roller being adapted to partake of the speed of the first roller notwithstanding a different speed of the plate-feeding mechanism.

16. Means for printing comprising mech-

anism for conveying a printing member, and mechanism for conveying an impression receiving member into coaction, and a platen adapted after coaction is established to feed the printing member and the impression receiving member together faster than the speed of the printing member conveyor.

17. In a printing device the combination of means for feeding a printing plate, means for feeding into conjunction therewith an article to be printed, there being provision for thereafter feeding the two together at the speed of the article, and means for causing said speed to be higher than that of the plate feeding means.

18. The combination of a rotary couple, means for feeding address plates and paper between them, the speed of rotation of one member of the couple being independent of the speed of propulsion of the address plates, and means for adjusting such speed of propulsion with reference to the peripheral speed of the other member of the couple.

19. The combination with a rotary paper feeding device, of means for propelling address plates into coaction with the rotary feeder which acts as a platen for the address plates and paper, and means for adjusting the speed of propulsion of the address plates so that the peripheral speed of travel of the platen may be the same as that of the address plate propelling mechanism or a multiple thereof.

20. The combination with a pair of co-operating rollers in proximity to each other, means at the opposite ends of one of the rollers for feeding address plates between the rollers, means for feeding paper between the address plates and the other roller, means for adjusting the speed of propulsion of the address plates, with reference to said other roller, the speed of rotation of the first mentioned roller being independent of the speed of propulsion of the address plates.

21. The combination of a pair of conveying devices adapted to feed address plates, a roller between said devices adapted to rotate independently of them, a rotary paper feeding device cooperating with said roller, and means for mutually adjusting the speed of travel of said devices and rotary paper feeder.

22. The combination of a pair of sprocket wheels, chains running over them and adapted to feed address plates, a roller between the sprockets adapted to rotate independently of them, a rotary paper feeding device cooperating with said roller, and means for mutually adjusting the speed of rotation of the sprocket wheels and rotary paper feeder.

23. In an addressing machine, the combination of printing mechanism, envelope feeding mechanism including a driving shaft therefor and mechanism operated by said shaft for carrying one or more envelopes to

the printing mechanism during each revolution of said shaft, with address plate feeding mechanism for carrying address plates to and through the printing mechanism, and 5 means for changing the relative rate of rotation of said shafts.

24. The combination with a rotary paper feeding device, of means for propelling address plates into coaction with the rotary 10 feeder, an independently movable platen co-acting with the rotary feeder to press together between them the address plates and paper, and two sets of gears for mutually adjusting the speed of propulsion of the address plates and paper, and means for rendering either set idle and the other active.

25. The combination of a rotary couple, means for feeding address plates and paper between them, the speed of rotation of one 20 member of the couple being independent of the speed of propulsion of the address plates, and a plurality of sets of gears for adjusting such speed of propulsion with reference to the peripheral speed of the other member 25 of the couple, and means for rendering either of said sets active and the rest idle.

26. The combination with a pair of co-operating rollers in proximity to each other, means at the opposite ends of one of the 30 rollers for feeding address plates between the rollers, means for feeding paper between the address plates and the other roller, a plurality of selective sets of gears for adjusting the speed of propulsion of the address plates 35 with reference to said other roller, the speed of rotation of the first mentioned roller being independent of the speed of propulsion of the address plates.

27. In an addressing machine, the combination of envelope feeding mechanism including a cylindrical platen and mechanism 40 operated therewith whereby one or more envelopes are carried to the printing mechanism in surface contact with said cylindrical 45 platen during each revolution, with address plate feeding mechanism for carrying address plates to and through the printing

mechanism, a printing roller loosely mounted in printing relation to said platen, two sets of gearing for transmitting motion from 50 one of said feeding mechanisms to the other, and means to render either set of gearing operative and the other inoperative.

28. In an addressing machine, the combination of envelope feeding mechanism including a shaft therefor, a cylindrical platen fixed to said shaft and means operated by said shaft for carrying one or two envelopes to and through the printing mechanism in surface contact with said platen during each 60 revolution of said shaft, with address plate feeding mechanism including a second shaft, two sprocket wheels fixed to said second shaft, two other sprocket wheels, two endless sprocket chains which embrace said sprocket 65 wheels and have outwardly projecting plate-engaging lugs, a plate magazine through the lower end of which the upper stretches of said chains pass, a platen roller loosely mounted on said second shaft between the sprocket 70 wheels thereon and in printing relation to the platen first mentioned, and means for variably transmitting motion from one of said shafts to the other.

29. In an addressing machine, the combination of envelope feeding mechanism including a shaft therefor, a cylindrical platen on said shaft and means operated by said shaft for carrying one or two envelopes to the printing mechanism during each revolution of said shaft, two gears of unequal diameter loosely mounted on said shaft, plate feeding mechanism for carrying address plates to and through the printing mechanism including a shaft therefor, two gears 80 of unequal diameter on the last mentioned shaft and in mesh with the two first gears mentioned, two of the four gears mentioned being loose, and mechanism for clutching either of said loose gears to its shaft. 90

In testimony whereof, I hereunto affix my signature.

CLIFTON CHISHOLM,
